UNITED STATES PATENT OFFICE.

PIETRO D'ALESSANDRO, OF SYRACUSE, NEW YORK, ASSIGNOR OF ONE-HALF TO
JOSEPH A. LAURY, OF SYRACUSE, NEW YORK.

POWDER-BRUSH.

1,173,781.

Specification of Letters Patent. Patented Feb. 29, 1916.

Application filed May 27, 1915. Serial No. 30,858.

To all whom it may concern:

Be it known that I, PIETRO D'ALESSANDRO, a citizen of the United States, residing at Syracuse, in the county of Onondaga and 5 State of New York, have invented certain new and useful Improvements in Powder-Brushes, of which the following is a specification.

This invention relates to improvements 10 to brushes, and the invention relates particularly to a combined brush and powder dispenser for use by barbers for carrying out certain work.

The object of the invention is to provide 15 a brush for use primarily for removing the cropped hairs from the face and neck of a patron like any ordinary dust brush.

A further object is to provide a hollow body and handle in which is stored a quantity 20 of talcum or like powder which is discharged into the brush, by means of a perforated base.

A further object is to provide a valve for controlling the passage of the powder from 25 the hollow handle to the brush. And a further object is to provide a novel manipulatable mechanism for operating the valve.

I attain these objects by the means set forth in the detailed specification which 30 follows, and as illustrated in the accompanying drawing in which—

Figure 1 is an elevational view of the complete device. Fig. 2 is a central longitudinal section, taken on line 2—2 of Fig. 1. 35 Fig. 3 is a view showing the several parts separated. Fig. 4 is a horizontal section, taken on line 4—4 of Fig. 1; showing the valve operating mechanism, the valve being closed. Fig. 5 is a similar sectional view; 40 showing the valve open. Fig. 6 is a top plan view of the body, taken on line 6—6 of Fig. 3; showing the valve closed. Fig. 7 is a horizontal section, taken on line 7—7 of Fig. 3; showing the perforations in the 45 brush-head relatively to the bristles.

In the drawing, the brush preferably comprises long bristles 2, which are set in the usual manner in a circular metallic head 3, the said head having its periphery externally 50 threaded, as at 4, for attachment to a cylindrical body 5, which is internally threaded at 6 to receive the said head. The bristles 2 are preferably arranged in a circle near the outer limits of the head, thereby leaving the 55 central portion of the head clear. The said

central portion is then provided with a plurality of perforations 7, for the passage of powder or liquid from the body 5 into the center 2' of the brush 2. The body 5 is provided with a transverse partition or head 8, which divides the said body into similar oppositely facing chambers or compartments 9 and 10. The opposite end of the body is internally threaded at 11 to receive the threaded open end of a handle 12, the said handle being hollow, at 12', for containing powder or liquid to be supplied to the brush 2. The partition 8 of the body 5 is preferably provided with several openings, as 13, and these openings are closed by a rotary valve 70 comprising a number of wings 14, which lie flat against the partition 8 on the side facing the handle 12, for sealing the said openings.

15 represents a spider which is disposed in the chamber 9 of the body 5. The free ends 75 16 of the arms of the spider are bent at right angles and are rigidly secured to the bottom sides of the valve wings 14, and by which the valve is rotated.

17 represents a series of push rods, which are reciprocatable in radial perforations formed in the wall of the body 5. The inner ends of the rods 17 are forked or slotted, as at 18. The push rods are positioned between the spider and the head 8, and the slot of each rod receives a pin 19 which is carried by the corresponding arm of the spider. The outer ends of the push rods 17 are enlarged and constitute push-buttons 20, which project outside of the peripheral surface 90 from the body. When either of the push rods 17 are pressed inwardly by the user of the brush they effect the partial rotation of the valve 14—14, from the position shown in Fig. 4, to that shown in Fig. 5, for opening the said valve. For greater convenience in operating the valve, I have provided 3 of the push buttons 20, and these are preferably spaced equidistantly around the periphery of the body 5. By this arrangement the 95 push buttons are conveniently accessible to either the thumb or fingers of the operator. When the operator presses inwardly on either of the push buttons, the rods 17, through their engagement with the pins 19 rotate the valve 14—14 sufficiently to open the windows 13. After pressure upon the push buttons is relieved, the valve is closed by a spring 22, one end of the spring being secured in a suitable manner, as at 23, to the 100

105 110

body 5, while the opposite end of the spring has a hook 24, which engages one of the claws 10 of the spider. The spring 22 exerts its tension for normally holding the 5 valve in the closed position shown in Figs. 4 and 6, for preventing the powder from passing from the handle and chamber 10 into the brush 2. Fig. 5 shows all of the 10 push rods 17 operated. But in practice it is only necessary to push one of the rods inwardly in order to effect the rotation of the valve 14—14.

My combined dust brush and powder dispenser is extremely simple and practicable, 15 and can be produced at small cost. By its use considerable time and labor may be saved, since heretofore, the dusting of the hairs after each clipping and then the powdering of the patron's neck have been accomplished by separate operations, and by 20 separate means.

It is obvious that some changes or modifications may be made of the parts of the device within the scope defined by the 25 appended claims without departing from the spirit of the invention.

Having thus described my invention, what I claim as new and desire to secure by Letters Patent, is—

30 1. In a valve for fountain brushes and the like, the combination with the substantially

flat seat having a plurality of radial openings, a valve adapted to bear upon one side of said seat and to rotate for opening and closing said openings, a spider-like support 35 disposed on the opposite side of the said seat having radial arms corresponding and attached to the arms of the said valve, a pin piercing the center of said seat and also said valve and said spider for pivotally mounting said movable parts, a plurality of push-rods reciprocatably supported by said seat and having slotted ends engaging the spider-arms for moving the said valve in one direction, and a spring for moving said valve in 45 the opposite direction.

2. In a valve of the class described, a seat having a plurality of radial openings, a valve rotatable on one side of said seat for controlling said openings, a spider disposed 50 on the opposite side of the said seat and having arms extending through the said openings and connected with the corresponding ports of the valve, means for pivoting said valve and said spider to the said seat, 55 a plurality of push rods having forked ends which engage pins carried by said spider for rotating said valve in one direction, and a spring for operating said valve and said push rods in the opposite direction. 60

In testimony whereof I affix my signature.

PIETRO D'ALESSANDRO.
